UNITED STATES PATENT OFFICE.

HARRY BRUNEL LEWIS, OF BROOKLYN, NEW YORK, ASSIGNOR TO BOORUM & FEASE COMPANY, OF NEW YORK, N. Y., A CORPORATION OF NEW YORK.

LOOSE-LEAF BINDER.

1,399,629.

Specification of Letters Patent.

Patented Dec. 6, 1921.

Application filed November 27, 1920. Serial No. 426,689.

To all whom it may concern:

Be it known that I, HARRY BRUNEL LEWIS, a citizen of the United States of America, residing at New York city, borough of Brooklyn, in the county of Kings and State of New York, have invented certain new and useful Improvements in Loose-Leaf Binders, of which the following is a specification.

My invention relates to loose-leaf binders, and particularly to improved means for securing to the binder cover the back plate of the binder mechanism.

In the accompanying drawings—

Figure 1 is a perspective of a binder cover showing my improved attaching means applied thereto;

Fig. 2 is a similar view showing the back plate in position; and

Figs. 3 and 4 are perspective views, respectively, of the back plate and anchor strip.

The loose-leaf binder to which my invention particularly relates is of the type shown in the Trussel Patent No. 779,142, dated January 3, 1905, the elements of which are illustrated in said patent and in improved form in the Patent No. 1,370,265 issued on March 1, 1921 to William C. Bardenbeuer. Inasmuch as the present invention is confined to the means for securing the back plate to the cover, the remaining details of the binder mechanism are omitted to avoid confusion.

The cover 5 of the binder may be of any suitable sort, say of leather, canvas, or lighter fabric, supported by card-board stiffeners, or the like, and may be provided with side pockets 6 and inner faces, but is in any event complete as a cover without the anchor strip 7, to which my invention relates. In a binder of the present type, the loose sheets are engaged by a binder mechanism of the type shown in the patent and application above referred to, which mechanism is mounted on a metal back plate 8. This back plate is of a width substantially corresponding to the back 9 of the binder, and the present invention relates to means for securing this back plate to the cover in a satisfactory manner without injury to, or material weakening of, the cover 5. For this purpose I use a strip of strong fabric, such as a strip of muslin or the like, which is stitched at 10 to the cover, the two lines of stitching being spaced apart substantially

the width of the back plate 8, but leaving free the marginal flaps 11 and 12 on opposite sides of the stitching. After the muslin strip, which for convenience I will term the "anchor strip", has been sewed to the cover, the back plate 8 is placed in position with its side margins substantially in register with the lines of stitches 10. The side flaps 11 and 12 of the anchor strip are then folded over the opposite edges of the back plate and trimmed to a width such that while they overlie the margins of the back plate, they leave exposed the lugs 13, 14 and 15 on the central area of the back plate, and by which the binder mechanism (not shown) is secured to the back plate. A suitable adhesive or cement applied either to the face of the back plate or to the flaps 11 and 12 serves to secure the flaps to the back plate, against which they are firmly pressed by the base of the binder mechanism when the latter is attached to the back plate. The flaps 11 and 12 are thus held in position, not only by the adhesive, but by the mechanical engagement of the base of the binder mechanism. The anchor strip 7 thus supports not only the back plate 8, but also the binder mechanism. The thread for the stitching 10 is of any suitable strength to meet the demands upon the appliance, and the spacing of the stitches is such that the needle holes do not pierce the cover so closely as to appreciably weaken the latter. Obviously the spacing of the stitches may vary with the material of the cover, fabric permitting a closer spacing of the stitches than leather without affecting the mechanical strength of the cover.

The underlying thought of the invention is to secure the binder mechanism supporting plate to the cover by means of a fabric strip stitched to the back of the cover, and I do not limit my invention to the precise form and arrangement of parts shown in the accompanying drawings.

I claim as my invention—

1. In a loose-leaf book, a cover, a back plate for supporting a binder mechanism arranged within the back of the book, and a fabric stitched to the cover and underlying said back plate, the opposite margins of said fabric being folded back over the back plate to hold the latter in position.

2. In a loose-leaf book, a cover, a back plate for supporting a loose-leaf binder mechanism within the back of the cover,

and a fabric strip interposed between said back plate and cover and stitched to the latter, and having marginal flanges overlapping the sides of the back plate and secured thereto.

3. In a loose leaf binder, a cover, a back plate for supporting a loose-leaf mechanism within the back of the cover, and having centrally arranged engaging devices thereon, in combination with a fabric anchor

strip stitched to the back of the cover and having side flaps overlying the side margins of the back plate and secured thereto, but leaving exposed said centrally arranged binder mechanism engaging elements on the 15 back plate.

In testimony whereof I have signed my name to this specification.

HARRY BRUNEL LEWIS.
